METHOD OF MAKING HINGES FOR DOORS
AND THE LIKEEric Sydney McCallum, Hurstville, New South
Wales, AustraliaApplication October 7, 1936, Serial No. 104,444
In Australia June 24, 1936

1 Claim. (Cl. 29—11)

This invention relates to hinges for doors, windows and the like, and provides improvements directed to effecting economy of time and material and to provide in the course of construction, 5 means whereby lubrication of the completed hinge is facilitated.

According hereto the tongues from which are formed the eyes of the two parts of the hinge through which the pivot pin passes, are, coincidentally with the operation of stamping them out from sheet metal, impressed with shallow recesses and punched with holes communicating therewith, in such manner that when the hinge is assembled, the concavities of the recesses are 10 towards the pivot pin, and form receptacles for lubricant which is passed into them through the said holes or from a channel hereinafter described.

A mode of carrying my invention into effect 20 is shown in the accompanying drawing wherein:—

Fig. 1 is a plan.

Fig. 2, a perspective view.

Fig. 3, a sectional elevation on the plane A—A,

Fig. 2, and

Fig. 4, a sectional plan.

Fig. 1 illustrates a manner of stamping out, 30 impressing and punching with holes, the wings 1 and 2 of the hinge from a strip 3 of metal which generally, as in common practice, will be in form of a coil carried upon a mandril, and drawn therefrom by mechanism associated with the press.

The wings and the tongues 4 upon wing 1, and 35 similar tongues 5 upon wing 2, are formed by stamping out the metal along lines 6, 7 and 8, the tongues 4 being subsequently bent to form cylindrical eyes 9, see Figs. 2, 3, and 4, which fit between similar eyes 10 formed from the tongues 5.

A pivot pin 11 passes through all the eyes in 40 the usual manner.

Concurrently with the stamping out of the

wings, the surfaces of the tongues which, when the eyes are formed, will be innermost, are impressed with a series of shallow recesses 12, each of which, as shown in Fig. 1, overlaps one of the tongues 4 and one of the tongues 5. Holes 13 communicating with the recesses are simultaneously punched as also are the usual screw holes 14.

A shallow recess 15 impressed in the edge of each of the outer tongues 4, forms, when the tongue is bent into an eye, a receiving channel 17 10 for lubricant which passes therefrom into the adjacent recess.

The recesses are so shallow that the outer surfaces of the eyes is not affected and consequently no obstruction is presented to the turning of 15 the hinge upon its pivot in the usual way.

As shown in Figs. 3 and 4 the formation of the tongues 4 and 5 into eyes, produces from the shallow recesses in the inner faces thereof a 20 series of receptacles for lubricant which is passed thereinto in the manner described.

The invention has been illustrated and described as applied to butt hinges but it will be understood that the lubricating device is applicable to hinges generally and that in the case 25 of hinges made from cast metal the recesses may be produced by the mould.

When considered advisable the surface of the pivot pin may be grooved to convey lubricant 30 from one recess to those below it.

I claim:—

In the manufacture of butt hinges, stamping out, at one operation, the two wings of the hinge and the tongues from which the eyes are formed, and simultaneously therewith impressing the 35 surface of the tongues with shallow recesses, and punching holes through the tongues whereby when the eyes are formed, shallow receptacles for lubricant are produced and the holes led thereinto.

ERIC SYDNEY McCALLUM
